ELECTRIC HEATING SYSTEM FOR
GARMENTS AND OTHER OBJECTSUscher Munschak, New York, N. Y., assignor of
one-half to Jacob Wolodarsky, Paris, FranceOriginal No. 2,284,673, dated June 2, 1942, Serial
No. 335,515, May 16, 1940. Application for re-
issue May 25, 1943, Serial No. 488,445. In France
June 1, 1939

17 Claims. (Cl. 219—46)

This invention relates to electric heating systems which may be used in garments, covers, cushions and in structures, which have their operation and heating effect indirectly controlled by and dependent upon the temperature of the surrounding air or other fluid.

The main object of my invention is to have a heating system of the character indicated which automatically maintains a uniform temperature of an object to which it is applied despite variation of low temperatures prevailing in the ambient fluid about said object.

The growing development of aviation and the tendency to fly at the highest possible altitudes have rendered necessary the use of electrically heated garments.

The experiences made till now have not entirely succeeded, as the heating systems employed not being provided with regulating means or having an ineffective regulation by means of the actuation by hand of an electrical current switch, were unable to ensure the automatic stabilization of the garment's temperature at a predetermined and fixed value.

The present invention also has as an object the construction of a safety electrically heated garment with automatic regulation of its temperature at a predetermined value, without considerable variations. In order to attain such object, several means are essentially combined according to the invention, in the constitution of the said garment.

The invention will be better understood with the aid of the following description and of the accompanying drawings, which show, by way of nonrestrictive example, one of its embodiments.

The garment itself: combined aviator garments, flying suits, coats, jackets, vests, waist-coats, trousers, socks, gloves, shoes, head and face garments, helmets, face masks and the like, is made of leather, fur, wool cloth or any other suitable material.

It is provided with a suitable lining, like an ordinary garment. Between the garment and the lining is mounted a flexible wire heater. Between the said heater and the garment's fabric is inserted a layer of heat insulating material which may be made of any kind of cotton, wool or silk wadding or with any other kind of heat insulating fabric. The heater and the heat insulating layer extend through the entire surface of the garment.

The electrical heater is bounded by two layers of waterproof and dielectric fabric. On the whole surface are formed, by means of lines of par-

allel stitchings binding together the two waterproofed fabric layers, sheaths or channels in which heating cords are lodged. The number and measures of such channels are determined by the number of heating cords to be lodged. These heating cords are formed with an asbestos core surrounded by a conducting wire working as an electric resistance, the whole being covered with a brading consisting in an asbestos layer forming a fireproof medium around the resistance layer. The measures of the resistance wire are determined by the electrical voltage and current with which the garment is to be fed.

Figures 1 and 2 of the accompanying drawings show, respectively in elevation and in transversal section, part of the garment together with its heater. On these figures TV is the fabric layer of the garment; MI is the layer of fireproof material; TC are the external layers of waterproof fabric, of the heater; TD is the lining fabric and C are the channels or sheaths in which the heating cords are recessed, these channels resulting from the binding together of the two fabric sheets TC; the stitching lines are shown in broken lines on Figure 2.

The electrical heating is thus ensured by means of heating cords CC of Figures 1 and 2.

For the automatic heating regulation there are generally used various automatic devices, designed to work in a medium more or less homogeneously heated. As these circumstances do not prevail in the case of the heating of garments, the automatic regulation of the temperature of the heating garment, according to the invention, is indirectly made, by using small special automatic regulators, for adjusting the temperature of the resistance wires, each of such wires being homogeneously heated over its whole length, when it is fed with electric current. It is sufficient to control the temperature in an only point of the resistance wire of each circuit, in order to reach an homogeneous regulation of the heater over its whole extension. The temperature of the garment establishing itself as a direct function of the heater's temperature, by this method an homogeneous regulation of the garment itself is reached.

In order to obtain a more homogeneous and precise regulation, the invention provides for a heating system with regulation of individual sections.

The heater is divided, over its entire area into several more or less equivalent sections, each of which is heated by means of a separately regulated heating element. Figure 3 shows diagram-

matically part of the heater in which some of the heating sections are provided with a separate regulation.

S_1 and S_2 are two sections or groups of distinct heating circuits, each of them being separately regulated, by means of one of the three regulators T_1 , T_2 , T_3 , and T_4 , T_5 , and T_6 .

Each section comprises three parallel connected resistance elements B_1 , B_2 , B_3 , or B_4 , B_5 , and B_6 , in series with resistance A or A_1 . The conductors of circuits S_1 , or S_2 are marked with sign + or -, according as they are connected with one or the other terminal of the source.

Two regulating methods are adapted, in order to be applied together or separately:

1. Regulation by intermittent flow of the electric current caused by the working of the automatic regulators inserted in each section and in each heating circuit.

2. Regulation by automatic series or parallel switching of the electric circuits of the resistance wires, by means of the electrical switching system resulting from the presence of the automatic regulators.

Figures 4, 5, 6, 7, and 8 relate to some details of this last regulation method by sections.

They diagrammatically show five different phases of the closing and opening of the automatic regulators or thermostats inserted in each heating section and mounted so as to work under the effect of the exterior temperature as it affects the relative temperature of the resistance wires.

Figure 4 shows the starting phase; there is visible on this figure heating element or section A in series with the three elements B_1 , B_2 and B_3 in parallel, when the three regulators T_1 , T_2 , T_3 are all locked, that is, on the contacting position.

Figure 5 shows a following phase, in which regulator T_2 is unlocked (that is, on the cutting off position) and regulators T_1 and T_3 are locked. Element A is visible, in series with element B_1 . The result will be equivalent with regulator T_2 , or T_1 and T_3 , or T_2 and T_3 , will be unlocked (the other regulator(s) being locked) that is, in all these cases, element A would be in series with a single element B .

Figure 6 shows a third phase, where the two regulators T_1 and T_2 are unlocked and the only regulator T_3 is locked. Element A is visible in series with elements B_2 , B_3 and B_1 , themselves in series one with the others.

Figure 7 shows a fourth phase of unlocking of the only regulator T_3 . There is visible element A in series with the two elements B_2 and B_1 , which are in parallel one with the other.

Figure 8 shows a fifth phase with all the three regulators T_1 , T_2 , T_3 unlocked. The current is seen to be interrupted everywhere and the heating is thus stopped.

In practice regulators T_1 and T_2 are adjusted with a slight advance at starting, with reference to regulator T_3 and so as to lock or unlock in synchronism one with the other, which in fact limits the whole regulating process to only three phases, viz. those of Figures 4, 6 and 8. It is easy to see that, in each phase the electrical resistance of the heating section is different, a circumstance which gives a variation of the electric current and a heating regulation. The cadence of the regulation may be chosen at will by varying the equivalent resistance and maintaining the whole current in each circuit group constituted by elements A and B variously and fourth resistances.

switched. If, for instance, there must be established an adjustment of 50% between the phase of Figure 4 and that of Figure 6, there can be deduced from formula:

$$2\left(A + \frac{1}{3}B\right) = (A + 3B)$$

that

$$A = \frac{7}{3}B$$

If A is the resistance of element A , expressed in ohms, B the resistance of each element B_1 , B_2 , B_3 expressed in ohms, the resistance of the phase of Figure 4 would be:

$$A + \frac{1}{3}B \text{ in ohms}$$

and the resistance of the phase of Figure 6 would be: $A + 3B$ in ohms, supposing that resistances are equal: $B_1 = B_2 = B_3$.

It is also possible to provide automatic switching system in series or in parallel with only B elements. For instance, Figure 9 shows a system of three B elements combined with two automatic regulators, giving: a first phase (Figure 9) of starting, when both regulators T_1 and T_2 are locked, the three elements being all in parallel and the resulting resistance being $\frac{1}{3}B$ ohm.

A second phase (Figure 10) with only one regulator locked, the resistance being B ohms.

A third phase (Figure 11) with both regulators unlocked, the three elements being in series and the resistance amounting to $3B$ ohms.

It is manifest that two or more heating sections S_1 and S_2 may be used simultaneously and connected in parallel, as for example already alluded to in Fig. 3, in which the sections A and A_1 are both connected in parallel to the current mains.

Having now fully described my invention, I claim:

1. An automatic electrical heating system adapted for use in garments, covers, cushions, fabrics and other objects, and effective to produce and maintain a stabilized, substantially uniform temperature for said garment or other object as a function of the temperature of the air or other fluid surrounding said garment or object, said system including a first resistance adapted for connection at one end to a source of current supply and at the other end having two branch circuits connected in parallel thereto, a thermostat having one pole thereof connected to one branch circuit and a second resistance connected to the other branch circuit, two further branch circuits connected in parallel to the other pole of said thermostat, a third resistance connected at one end to one of said further branch circuits and a fourth resistance connected at one end to the other of said further branch circuits, a conductor adapting the other end of the third resistance for connection to said source of current, connecting means connecting said conductor in parallel to the other ends of the second and fourth resistances, and at least one thermostat included in said connecting means between said second and fourth resistances and said conductor, at least one of the thermostats being set to open at a different temperature than the one or more other thermostats in the system.

2. An automatic electrical system according to claim 1, having an additional thermostat included in the connecting means between the sec-

3. An automatic electrical system according to claim 1, having the thermostats disposed adjacent portions of the resistances so as to be responsive to the temperatures thereof.

4. An automatic electrical system according to claim 1, having the thermostats disposed adjacent portions of the first resistance and also adjacent limited portions of at least one of the other resistances so as to be responsive to the temperatures thereof.

5. An automatic electrical system according to claim 1, having an additional thermostat included in the connecting means between the second and fourth resistances, and having the thermostats disposed adjacent portions of the first resistance and also adjacent limited portions of at least one of the other resistances so as to be responsive to the temperatures thereof.

6. An automatic electrical heating system adapted for use in garments, covers, cushions, fabrics, and other objects, and effective to produce and maintain a stabilized, substantially uniform temperature for said garment or other object as a function of the temperature of the air or other fluid surrounding said garment or object said system including a first resistance adapted for connection at one end to a source of current supply and at the other end having two branch circuits connected in parallel thereto, a thermostat having one pole thereof connected to one branch circuit and a second resistance connected to the other branch circuit, further branch circuits connected to the other pole of said thermostat and to the other end of the second resistance, a plurality of resistances individually included in some of said further branch circuits, connecting means serving to connect all of said further branch circuits to the source of current supply, and at least one additional thermostat included in said connecting means between at least one of said further branch circuits and said current source.

7. An automatic electrical system according to claim 1, in which the system is repeated so that each system forms a single section of the resulting multiple or plural system, and in which all systems or sections are connected in parallel.

8. An automatic electrical system according to claim 6, in which the system is repeated so that each system forms a single section of the resulting multiple or plural system, and in which all systems or sections are connected in parallel.

9. An automatic electrical heating system adapted for use in garments, covers, cushions, fabrics and other objects, and effective to produce and maintain a stabilized, substantially uniform temperature for said garment or other object as a function of the temperature of the air or other fluid surrounding said garment or object, said system including a first resistance adapted for connection at one end to a source of current supply and at the other end having two branch circuits connected in parallel thereto, a thermostat having one pole thereof connected to one branch circuit and a second resistance connected to the other branch circuit, two further branch circuits connected in parallel to the other pole of said thermostat, a third resistance connected at one end to one of said further branch circuits and a fourth resistance connected at one end to the other of said further branch circuits, a conductor adapting the other end of the third resistance for connection to said source of current, connecting means connecting said conductor in parallel to the other ends of the

second and fourth resistances, an additional thermostat included in said connecting means between said other ends of the second and fourth resistances and said conductor, and a third thermostat also included in said conducting means between one of said last mentioned two resistances and the additional thermostat.

10. An electrical heating system for use in an aviator's garment and effective to produce and maintain a stabilized temperature for said garment as a function of the temperature of the air surrounding said garment, said system including a first resistance having a substantially constant ohmic value during the operation of said system and adapted to be connected directly to a source of electric energy, and a second resistance comprising two or more heating wires interconnected in parallel to provide a given ohmic resistance, a plurality of thermostats operatively connected to said heating wires for automatically varying the ohmic resistance of said second resistance as a function of the heat generated in the said system by the flow of current and of the fluid surrounding said system and for automatically placing two or more of said heating wires in series, means operatively connecting said second resistance to said first resistance in series and means operatively connecting said second resistance to said source of electric current, the flow of current through the first resistance being varied but not interrupted by the opening or closing of any one of said thermostats.

11. In an electrical heating system of the class described, a first resistance adapted to be connected to a source of current and means operatively connected in series to said first resistance and to said source of current, said means including two or more resistances connected in parallel and having a predetermined ohmic value, and thermostats operatively connected to said two or more resistances and adapted to be automatically opened and closed in accordance with the temperature generated in said resistances by the flow of current and in accordance with the temperature of the medium surrounding the system, said thermostats being adapted to place two or more of said resistances in series and the flow of current through the first resistance being varied but not interrupted by the opening or closing of any one of said thermostats.

12. An electrical heating system according to claim 11 wherein one of said thermostats is connected in series with at least two of the resistances connected in parallel.

13. An electrical heating system of the class described including three resistances adapted to be connected to a source of current, means interconnecting one end of each of said resistances in parallel, means connecting the other ends of each of said resistances in parallel, a thermostat connected between the first two of said resistances, and a second thermostat connected between the opposite ends of the second and third resistances, said thermostats being disposed in parallel between two parallel connected resistances, and means for connecting said resistances to a source of current.

14. An electrical heating system formed of a plurality of independently regulated sections, each section comprising a first resistance connected to a source of current, a plurality of heating wires, means for connecting said wires in parallel and to said first resistance, means for connecting said wires to said current source, and thermostats operatively connected to said first

named means for connecting two or more of said wires in series, the flow of current from said source through said first resistance being changed by the opening or closing of any one of said thermostats.

15. In a heating circuit of the class described, a first resistance adapted to be connected at one end thereof to a source of current, a second resistance comprising at least three resistance elements in parallel, the opposite end of the first resistance being connected in series to said resistance elements, a thermostat interposed between the first resistance element and the second resistance element at one end thereof, a second thermostat interposed between the second resistance element and the third resistance element at the opposite end thereof, and means for connecting said opposite end of the third resistance element to a source of current.

16. In a heating system of the class described, three resistances, means connecting adjacent ends of each resistance, means connecting the other ends of each of said resistances whereby the three resistances are connected in parallel, a thermostat interposed in the first-named connecting means between the first and second resistances, a thermostat interposed in the second-named connecting means between the second and

third resistances whereby the opening of both thermostats is effective to place all three of said resistances in series, and means for connecting the opposite ends of the first and third resistances to a source of current.

17. In a heating system of the class described, a first resistance operatively connected at one end to a source of current and at the other end having two branch circuits connected in parallel thereto, a thermostat having one pole thereof connected to one branch circuit and a second resistance connected to the other branch circuit, two further branch circuits connected in parallel to the other pole of said thermostat, a third resistance connected at one end to one of said further branch circuits and a fourth resistance connected at one end to the other of said further branch circuits, a conductor connecting the other end of the fourth resistance directly to a source of current, conducting means connecting said conductor in parallel to the other ends of said second and third resistances, and thermostat means included in said conducting means between said other end of the fourth resistance on the one hand, and the other ends of at least one of the pair formed by the second and third resistances.
